DESIGN FOR A CONNECTING LINK FOR A NECKLACE OR SIMILAR ARTICLE

Robert Gardel, New York, N. Y.

Application December 24, 1947, Serial No. 143,317

Term of patent 7 years

(Cl. D45—4)

To all whom it may concern:

Be it known that I, Robert Gardel, a citizen of the United States of America and a resident of New York city, in the county and State of New York, have invented a new, original, and ornamental Design for a Connecting Link for a Necklace or Similar Article, of which the following is a specification, reference being had to the accompanying drawing, forming part thereof.

Fig. 1 is a front view of a connecting link for a necklace or similar article;

Fig. 2 is a section taken on line 2—2 of Fig. 1; and

Fig. 3 is an end view.
The dominant features of my design reside in the portions shown in full lines.

I claim:

The ornamental design for a connecting link for a necklace or similar article, substantially as shown and described.

ROBERT GARDEL.
